UNITED STATES PATENT OFFICE.

RICHARD W. THICKINS, OF MINNEAPOLIS, ASSIGNOR OF ONE-HALF TO
EDWARD R. HARROUN, OF ST. PAUL, MINNESOTA.

CAR-DOOR.

SPECIFICATION forming part of Letters Patent No. 450,125, dated April 7, 1891.

Application filed September 10, 1887. Serial No. 249,383. (No model.)

To all whom it may concern.

Be it known that I, RICHARD W. THICKINS, a citizen of the United States, residing at Minneapolis, in the county of Hennepin and State of Minnesota, have invented certain new and useful Improvements in Sliding-Door Hangers, of which the following is a specification.

This invention relates to sliding doors; and it consists in the construction and arrangement of the hangers and method of constructing and operating the door, as hereinafter shown and described, and specifically pointed out in the claims.

This invention may be applied to any form of sliding door which is arranged to travel upon a track or tracks, but is more particularly applicable to the doors of freight-cars, and for the purpose of illustration I have shown it in the drawings applied to such a purpose.

In the drawings, Figure 1 is a side elevation of a portion of a car and one of its doors, with the door partially open, showing my improvements attached thereto. Fig. 2 is a similar view with the door closed. Fig. 3 is a cross-sectional view on the line W W of Fig. 1. Fig. 4 is a cross-sectional view on the line X X of Fig. 2. Fig. 5 is a plan view of the door-operating mechanism and a portion of the car-frame, illustrating more fully the construction. Fig. 6 is a sectional detail of the door and a portion of the car-frame, illustrating the manner of constructing the weather-strips. Figs. 7, 8, 9, and 10 are detached views of the cam-shaft, Fig. 7 being in cross-section on the line Y Y of Fig. 8, and Fig. 9 being in section on the line Z Z of Fig. 10. Figs. 11, 12, and 13 are sectional details similar to Fig. 6, illustrating modifications in the construction of the weather-strips. Fig. 14 is a side view of a portion of a car and one of its doors, illustrating a modification of the construction of the operating mechanism. Fig. 15 is a plan view of Fig. 14. Fig. 16 is a cross-section on the line V V of Fig. 14, showing the door ready to be inserted into the doorway-opening; and Fig. 17 is a similar view showing the door closed into the opening.

A' represents a portion of the body or sides 50 of the car; A², a portion of the roof; A³, a portion of the floor; A⁴, the doorway-opening; A⁵, a portion of the door; A⁶, the lower track on which the door travels, and A⁷ the upper track, which supports the upper edge of the door, 55 all these parts being constructed in the ordinary manner.

The door A⁵ when open sets with its inner face out from the side A' of the car, as shown, so as to slide clear of the car, and will be so 60 mounted upon the track as to be raised upward and forced inward when in the proper position opposite the opening A⁴, this action and the means whereby it is accomplished being the principal object of my invention. 65

Upon each of the lower corners of the door A⁵ a plate B' will be attached, each plate having journaled in its lower edge a cam-shaft B². Only one of these plates B' and only one side of the door A⁵ are shown in Fig. 1; 70 but it will be understood that each lower corner of the door will be provided with one of the plates and cam-shafts.

Each of the cam-shafts is formed with a recess a near one end, the inner surface of the 75 recess being in line with the upper line of the track A⁶, so that when the recess is downward the center line of the cam-shaft is on a line with the upper line of the track, as shown in Fig. 7, which represents a cross-section of 80 the cam-shaft on the line Y Y of Fig. 8. When the cam-shafts are in this position, they are mere guides by which the door is moved backward and forward on the track A⁶ and parallel with it, and have no other function so long 85 as the cam-shafts are not revolved in their bearings in the plates B'.

Near the outer end of each cam-shaft a lever B³ is secured in any suitable manner, but preferably by a square hole fitting a square 90 socket on the cam-shaft, as shown, the action of this lever being to revolve the cam-shaft and cause it to assume the position shown in Fig. 9, and thus elevate the door the distance of one-half the diameter of the cam-shaft. 95

Each of the cam-shafts is formed with a cam rib or lug a', whose function it is to run down behind the upper edge of the track and

move the cam-shaft inward toward the side of the car and through its connection to the door by the plate B'. This action, as will be readily understood, will cause the lower edge 5 of the door to be moved inward and pressed against the side of the car.

Each of the upper corners of the door A⁵ will be provided with a plate D', in which a forked arm D² is pivoted, the forks embracing 10 the upper guide A⁷, as shown. When the door A⁵ is in its downward position, the forked arm D² is inoperative; but when the door is elevated by the revolving of the cam-shafts the forks of the arm by embracing the 15 upper track roll beneath the under and inner sides of the upper track and transform the forked arms into "toggle-levers," and thus force the upper edge of the door inward and keep it parallel with the car in its upward 20 and inward movement.

The action of the forked arms is two fold: first, moving the door inward at the same time that it is raised by the cam-shafts, and, second, forming braces to hold the door 25 pressed against the side of the car or into the doorway-opening.

In Figs. 14, 15, 16, and 17 a slight modification in the construction is shown, which will generally be adopted when the door is to be 30 set bodily into the doorway-opening of the car, as this arrangement permits of a greater movement to the door than that shown in Fig. 1; but the construction, mode of operation, and results produced are substantially the 35 same in both arrangements.

In the construction shown in Figs. 14, 15, 16, and 17 the bar D² is formed without the forked feature, and is pivoted by its upper end to the side of the car and adapted to act 40 by its lower end against projections b' on the upper corners of the door to throw the door inward at the same time it is elevated by the cam-shafts, the action and functions of the bar D² being precisely the same as in the construction shown in Figs. 1, 2, 3, and 4—viz., to move the door inward at the same time that it is elevated, and to also serve as a brace to hold the door pressed into the doorway-opening. In both forms the upward pressure on 45 the door increases the inward pressure, so that the close contact of the door against the car or into the doorway-opening is assured. The lower ends b² of the toggle-levers D² and corresponding faces of the lugs b' will be beveled, as shown in Fig. 15, so that their contiguous surfaces will be sure to run in contact when the door is closed and prevent any slight side play from preventing the proper contact. The cam-shafts E² have cam-ribs 55 a² near the outer ends, which pass down outside the track A⁶ when the shafts are revolved and serve to draw the door outward when the cam-shaft is revolved backward, the two sets of cam-ribs a' a², together with the cam-shafts, forming a screw-like conformation, as 60 shown.

Each of the plates B' will be provided with

an anti-friction roller B⁶, to run upon the track A⁶ when the door is in its lowermost position to carry the door and prevent all the 70 strains coming upon the cam-shafts, these rollers being inactive when the door is elevated.

Attached to the frame of the car alongside the doorway-opening is a plate E', having a 75 small lever or catch E² pivoted to it, the free end of this catch having a projecting perforated lug g', against which a similar projecting lug g² on the lever B³ strikes when the lever is thrown over in elevating the door, as 80 shown in Fig. 2, the perforations in the two lugs forming a means for securing the door by a lock or "seal." The lever B³ projects beyond the lug g² a short distance, as shown at g³, this projecting portion adapted to fit into 85 a cavity in the lower part of the catch E², so that the lever B³ will be held in the position shown in Fig. 2. The projecting end g³, when the lever is thrown over to the left, strikes the inclined face g⁴ of the catch and lifts it 90 upward, and passes into the cavity, the catch falling down again into its former position and holding the lever securely. The lugs g² are not necessary to the security of the connection between the catch and lever, as the 95 projecting end g³ will hold them intact; but the lugs form a convenient means for attaching a lock or seal to the door. The plate E' is provided with two stops h' h², which coact with a stop h³ on the catch E² to limit the 100 movement of the catch and prevent it falling too far downward or from being thrown too far upward.

In the construction shown in Fig. 14 one of the plates B', with its cam-shaft B², is attached 105 to the center of the door A⁵, while the outer lower corners are supplied with plates F', each connected by links F² to rider-plates, bearings, or shoes F³, adapted to rest upon and slide along the track A⁶, as shown. When 110 the door is in its lowermost position, the lower surfaces of the plates F' and the upper surfaces of the rider-plates F³ lie in contact, and then when the door is elevated by the cam-shaft the links F² are lifted with the ends of 115 the door and throw the lower edge of the door over into its opening A⁴, as shown in Fig. 17. It will be noted that the pivots of the link F² extend horizontally, so that the link swings in a vertical plane, whereby the door when 120 opened and moved bodily outward from the outer face of the car is slightly lowered.

The rider-plates F³ are each provided with a downwardly-hanging lip or projection F⁴, which covers the track A⁶, and each lip is 125 provided with a cavity d', which passes over the heads d² of the bolts d³, by which the tracks are secured to the car-frame. The bolts will be so arranged that when the door A⁵ is opposite the opening A⁴ and ready to be 130 elevated and placed back into position the cavities d' in the lips F⁴ will be opposite the heads d² of the bolts, so that when the door is elevated the tendency of the rider-plates

to be thrown upward will be counteracted by the lips F^4 catching upon the heads d^2 .

Each of the cam-shafts B^2 may be provided with an arm B^4 , adapted to project forward 5 and downward and strike a stop H , attached to the car A' near the ends of the travel of the door to automatically revolve the cam-shaft when the door is near the end of its stroke in closing, the two positions of the cam-shaft being shown in Figs. 7 and 9.

Two of the bolts d^3 , by which the track A^6 is connected to the car-frame, will be so arranged that the arms B^4 of the cam-shaft will pass over them and be turned down behind 15 them when revolved to operate the door, so that when the door is to be opened the act of pushing it backward along its tracks will cause the arms B^4 to catch upon the bolts d^3 and throw the cam-shafts backward into their 20 first position, and thus draw the door outward and downward ready to be moved along the tracks.

The presence of the arms B^4 and stops H are not a necessary part of the invention, as 25 the lever B^3 may be operated by hand; but by the use of the arms and stops the action is rendered automatic and the doors are more easily operated.

The edges of the door A^5 are provided with 30 inwardly-projecting ribs or plates M' , which are rigidly secured or attached to the door, and are adapted to fit into grooves M^2 in the face of the car or behind corresponding strips M^3 on the edges of the doorway-opening, the 35 strips being preferably inclined, as shown, so that the act of drawing the door up against the car will also draw the strips M' in closer contact with the strips M^3 or into the grooves M^2 , and thus form a very close-fitting joint 40 around the doorway, which will thoroughly exclude the elements. These strips M^3 may be made in any desired form or construction; but for the purpose of illustration I have shown several modifications of the strips, but 45 they are substantially the same in all the modifications and produce the same results.

In Figs. 1, 2, 3, 4, 5, and 6 the strips M^3 are beveled and fit into beveled grooves in the car-frame around the doorway-opening, the 50 strip on the rear edge of the door, as before stated, fitting behind a correspondingly-beveled strip on the rear edge of the doorway-opening. The location of this strip M^3 is clearly shown in Fig. 6. A similar strip M^4 55 will also be generally attached to the other edges of the doorway-opening, so as to furnish a uniform bearing-surface for the inner surfaces of the door and also to increase the bearing-surfaces of the strip.

In Fig. 11 a slight modification in the manner of arranging the strips M' and M^3 on the rear edge of the door is shown, consisting in employing two sections of "L-iron," one on the door and one on the car and set at an angle, and 60 forming the grooves M^2 to correspond, so that when the door is closed the joint contains a greatly-increased bearing-surface, forming a

circuitous passage for the air in escaping or entering, and more effectually excluding dust and rain or snow.

The construction shown in Fig. 11 will be more particularly applicable to refrigerator-cars, and for similar constructions requiring a very tight joint.

In Fig. 12 a construction is shown similar 75 to Fig. 11, so far as an increased bearing-surface in the joint is concerned, while in Fig. 13 a construction is shown similar to that in Fig. 6, the strip M^3 being formed of a metal plate attached at an angle to the side of the 80 doorway-opening. If desired, the levers B^3 of the two cam-shafts might be united by a rod, so that both would be operated together and by one operation. The levers B^3 will each be provided with a handle B^5 , by which 85 they may be more easily operated.

In the construction shown in Figs. 14 and 15 the plate B' will be provided with a perforated projection g^5 , against which the projection g^2 on the lever B^3 will rest when the lever 90 is thrown over to raise the door to form a stop to the lever, and also to provide means for the insertion of a lock or seal. The lug or projection g^5 thus serves the same purpose as the similar lug g' . (Shown in Fig. 1.) If 95 preferred, one of the plates E' and catches E^2 might be attached to the door contiguous to the lever B^3 , as in Fig. 1.

Having thus described my invention, what I claim as new is—

1. In a door arranged to be moved laterally upon a track or tracks to cover and uncover the doorway-opening, one or more cam-shafts B^2 , having screw cam-ribs and adapted to travel with said door upon said track or tracks, 105 whereby by the revolution of said cam-shafts said door may be elevated and pressed against said car or into the doorway-opening, substantially as and for the purpose set forth.

2. In a door arranged to be moved laterally 110 upon a track or tracks to cover and uncover the doorway-opening, one or more cam-shafts B^2 , having screw cam-ribs and adapted to travel with said door upon said track or tracks, and one or more toggle arms or levers D^2 , 115 pivoted on or near the upper edge of said door, whereby by the revolution of said cam-shafts said door may be elevated and pressed against said car or into the doorway-opening, substantially as and for the purpose set forth.

3. In a door arranged to be moved laterally 120 upon a track or tracks to cover and uncover the doorway-opening, one or more cam-shafts B^2 , having screw cam-ribs and adapted to travel with said door upon said track or tracks, 125 and a lever-arm B^3 , attached to said cam-shaft, whereby the latter may be operated, in combination with pivoted latch E^2 , substantially as and for the purpose set forth.

4. The car having outwardly-projecting 130 strips M^3 at one or more edges of the doorway-opening and a sliding door having inwardly-projecting strips M' , rigidly attached on one or more of its edges, whereby when

said door is closed the strips on said door overlap the strips on said car, substantially as and for the purpose set forth.

5. A car having a doorway-opening and provided with inwardly-extending grooves on its outer face along one or more margins of said doorway-opening, in combination with a sliding car-door sliding on the exterior of said car and capable of being moved bodily to and 10 from the outer face of the car, said door having strips on or near one or more of its edges projecting inwardly beyond the inner face of said door, said strips being rigidly attached to the door and adapted to fit in said grooves 15 in the outer face of the car, substantially as set forth.

6. A car having a doorway-opening and provided with inwardly-extending grooves on its outer face along one or more margins of said doorway-opening, each of said grooves having at least one face extending at an angle to the face of the car, in combination with a sliding car-door sliding on the exterior of said car and capable of being moved bodily to and 20 from the outer face of the car, said door having strips on or near one or more of its edges projecting inwardly at an angle beyond the inner face of said door, said strips being rigidly secured to the door and adapted to fit in 25 said grooves in the outer face of the car, substantially as set forth.

7. The car-door having strips on or near one or more of its edges and projecting past the

inner face thereof and made integral therewith, in combination with a car having grooves 35 in its face corresponding with said projecting strips, said door having cam-shafts supporting its lower edge, whereby it is capable of being lifted bodily and forced inward to cause said strips to enter said grooves, substantially as and for the purpose set forth.

8. In a door arranged to be moved laterally upon a track or tracks to cover and uncover the doorway-opening, one or more cam-shafts B², having screw cam-ribs and adapted to 40 travel with said door upon said track or tracks, and a lever-arm B³, having perforated lug g², in combination with pivoted latch E², having correspondingly-perforated lug g¹, substantially as and for the purpose set forth. 50

9. In a door arranged to be moved laterally upon a track or tracks to cover and uncover the doorway-opening, one or more cam-shafts B³, having screw cam-ribs and adapted to travel with said door upon said track or 45 tracks, in combination with supporting-plates F', attached to said door at or near its lower corners, rider-plates F¹, adapted to embrace and travel upon said track and having recessed lips F², and links F³, connecting said 55 rider-plates and supporting-plates, substantially as and for the purpose set forth.
